[57] ABSTRACT

An internal latent image type silver halide photographic emulsion which provides a direct positive image by surface development in the presence of a fogging agent and which is useful in a light-sensitive material for the diffusion transfer process, which emulsion is spectrally sensitized with a supersensitizing combination of at least one sensitizing dye represented by the following general formula (I) or (II)

(I)

wherein Z_1 represents a non-metallic atomic group necessary to complete a 5- or 6-membered heterocyclic ring; and R_1 and R_2 , which may be the same or different, each represents an alkyl group;

(II)

wherein Z_2 represents a non-metallic atomic group necessary to complete a 5- or 6-membered heterocyclic

ring; R_3 represents an alkyl group or an aryl group; R_4 represents an alkyl group or a substituted alkyl group; R_{18} represents a hydrogen atom or an alkylene group necessary to complete a ring when R_4 and R_{18} combine to form a ring; and Y represents an oxygen atom or $=N-R_{19}$ wherein R_{19} represents a hydrogen atom, an alkyl group or an aryl group; and at least one sensitizing dye represented by the following general formula (III), (IV), (V), (VI) or (VII)

(III)

wherein V_1 , V_2 , W_1 and W_2 , which may be the same or different, each represents a hydrogen atom, a halogen atom, a trifluoromethyl group, a cyano group, a carboxy group, an alkoxy carbonyl group, an aminosulfonyl group or an alkylsulfonyl group; R_5 , R_6 , R_7 and R_8 , which may be the same or different, each represents an alkyl group or a substituted alkyl group; X_1 represents an acid anion; and n_1 represents 0 or 1;

(IV)

wherein V_1 , V_2 , R_5 and R_6 , which may be the same or different, each has the same meaning as defined in general formula (III); R_9 , R_{10} and R_{11} , which may be the same or different, each represents an alkyl group or a substituted alkyl group; X_2 represents an acid anion; n_2 represents 0 or 1; and W_3 and W_4 , which may be the same or different, each represents a hydrogen atom, a halogen atom, an alkyl group, an alkoxy group, a hydroxy group, an acyloxy group or a phenyl group;

wherein V_1 , V_2 , R_5 and R_6 , which may be the same or different, each has the same meaning as defined in general formula (III); W_5 and W_6 , which may be the same or different, each represents a hydrogen atom, a halogen atom, an alkyl group, an alkoxy group, a hydroxy group, an acyloxy group or a phenyl group; R_{12} represents an alkyl group or a substituted alkyl group; X_3 represents an acid anion; and n_3 represents 0 or 1;

wherein V_3 and W_7 , which may be the same or different, each represents a hydrogen atom, an alkyl group, an alkoxy group, a hydroxy group, an acyloxy group or a phenyl group; R_{13} represents an alkyl group; R_{14} and R_{15} , which may be the same or different, each repre-

sents an alkyl group or a substituted alkyl group; X_4 represents an acid anion; and n_4 represents 0 or 1;

wherein V_4 represents a hydrogen atom, a halogen atom, an alkyl group, a hydroxy group, an acyloxy group or a phenyl group; Z_3 represents an oxygen atom, a sulfur atom, a selenium atom or $-\text{CH}=\text{CH}-$; W_8 and W_9 , which may be the same or different, each represents a hydrogen atom, a halogen atom, an alkyl group, an alkoxy group, a hydroxy group or a phenyl group; R_{16} and R_{17} , which may be the same or different, each represents an alkyl group or a substituted alkyl group; X_5 represents an acid anion; and n_5 represents 0 or 1.
